United States Patent

Des. 242,129
Patented Nov. 2, 1976

242,129

CONTAINER END PANEL

Gary K. Hasegawa, Morton Grove, and Carmen T. Mascia, Westmont, Ill., assignors to Continental Can Company, Inc., New York, N.Y.

Filed June 12, 1975, Ser. No. 586,489

Term of patent 14 years

Int. Cl. D9—99

U.S. Cl. D9—253

FIG. 1

FIG. 4

FIG. 2

FIG. 3

FIG. 1 is a top plan view of a container end panel showing our new design;

FIG. 2 is an edge view thereof;

FIG. 3 is a bottom plan view thereof; and

FIG. 4 is a cross-sectional view taken on line 4—4 of FIG. 1 through the aperture area.

We claim:

The ornamental design for a container end panel, as shown and described.
